CLAIM

The ornamental design for a dispenser for personal care compositions, as shown and described.

DESCRIPTION

Figure 1.1 is a perspective view of a dispenser for personal care compositions embodying our new design;

Fig. 1.2 is a front view thereof;

Fig. 1.3 is a back view thereof;

Fig. 1.4 is a left view thereof;

Fig. 1.5 is a right view thereof;

Fig. 1.6 is a top view thereof;

Fig. 1.7 is a bottom view thereof.

The broken lines depict portions of a dispenser for personal care compositions that form no part of the claim.

1 Claim, 3 Drawing Sheets
